(57) **CLAIM**

The ornamental design for a shelf supporter for furniture, as shown and described.

DESCRIPTION

FIG. 1 is a plan view of a shelf supporter for furniture embodying my new design;

FIG. 2 is a front view thereof;

FIG. 3 is a bottom view thereof;

FIG. 4 is a left side view thereof;

FIG. 5 is a rear view thereof;

FIG. 6 is a sectional view taken along line 6—6 of 1 thereof;

FIG. 7 is a perspective view thereof; and,

FIG. 8 is a reduced scale environmental view referential figure showing a state of use 1 thereof.

The broken line showing of partial shelving structure is for illustrative purposes only and forms no part of the claimed design.
